CLAIM

I claim the ornamental design for a utensil and condiment holder, as shown and described.

DESCRIPTION

FIG. 1 is an elevated perspective view of the utensil and condiment holder of the claimed design;

FIG. 2 is a front view of the utensil and condiment holder of FIG. 1;

FIG. 3 is a back view of the utensil and condiment holder of FIG. 1;

FIG. 4 is a left side view of the utensil and condiment holder of FIG. 1;

FIG. 5 is a right side view of the utensil and condiment holder of FIG. 1;

FIG. 6 is a top view of the utensil and condiment holder of FIG. 1; and,

FIG. 7 is a bottom view of the utensil and condiment holder of FIG. 1.

1 Claim, 7 Drawing Sheets
